HORIZONTAL OUTPUT TRANSFORMER FOR TELEVISION RECEIVERS

William L. Hughes, North Syracuse, and Benjamin O. Powell, Liverpool, N.Y., assignors to General Electric Company, a corporation of New York
Continuation of application Ser. No. 539,702, Apr. 4, 1966. This application Feb. 13, 1968, Ser. No. 705,226
5 Claims. (Cl. 336—96)

ABSTRACT OF THE DISCLOSURE

This invention is directed to a horizontal output transformer having a primary winding assembly surrounded by an annular tertiary assembly which includes an open ended cylindrical coil form having a non-wax-impregnated layer-wound tertiary winding positioned thereon. The layers of the tertiary are separated by slow burning polyethylene terephthalate film. A naphthalene chloride wax corona tire surrounds the tertiary assembly and extends into the interstices between adjacent layers of the film.

This application is a continuation of application Serial No. 539,702, now abandoned, filed April 4, 1966.

The present invention relates to horizontal output transformers for television receivers and more specifically to an improved horizontal output transformer which will not support combustion.

A horizontal output transformer is employed in a television receiver to couple the horizontal sweep signal from the horizontal output stage to the deflection yoke and to develop the high voltage necessary for operation of the cathode ray tube. Such transformers also conventionally perform ancillary functions such as developing horizontal flyback pulses for application to the AGC keyer and developing blanking pulses for application to the cathode ray tube. The horizontal output transformer is thus a high voltage, high energy device and must be carefully designed to insure compliance with rigid safety standards.

In the prior art horizontal output transformer now employed throughout the industry, the primary and associated ancillary windings are positioned on a suitable coil form. An annular tertiary or high voltage winding is employed comprising a layer wound coil employing paper as the insulating material. The primary and associated ancillary windings are positioned in the central opening of the tertiary and affixed thereto. Since the insulating paper employed in the tertiary winding of such a device is hygroscopic it is necessary after the tertiary is assembled to the primary to impregnate the tertiary with wax material in order to prevent failure of the transformer due to absorption of water. After the tertiary is wax impregnated in this manner a discrete wax corona tire formed from a combustible wax is placed around the outer surface of the tertiary to prevent corona which would otherwise result in failure of the transformer.

Since the tertiary of the prior art transformer is necessarily wax impregnated and a combustible wax corona tire is employed, the prior art transformers are highly combustible. Accordingly, it is necessary for safety reasons to position the prior art transformer in a fire-proof cage or alternatively to overdesign the transformer to such an extent that electrical breakdown and subsequent combustion cannot take place. Neither of these approaches is completely acceptable and adds unwarranted expense to the cost of television receivers. For example, even though a fire-proof cage is employed, the burning of the transformer can result in expensive smoke damage to a user's home. Further, a transformer positioned in a fire-proof cage cannot be adequately ventilated and accord-

ingly operates at a relatively high temperature thereby lowering the reliability of the transformer.

Further, the requirement that the tertiary be impregnated with a wax material necessitates delays in assembly to allow time for curing the wax prior to the application of the corona tire to the tertiary. Even further, the prior art transformer is difficult and expensive to assemble since the tertiary has to be assembled to the primary through the use of an adhesive material which is compatible with the wax with which the tertiary is impregnated.

Additional problems are also found to be associated with the use of an impregnating wax. For example, such impregnating waxes often became "gassy" to such a degree that use of the "gassy" wax results in entrapping of air bubbles which would in turn result in corona and subsequent breakdown of the transformer. Further, since an impregnating wax as well as a discrete wax corona tire is necessary, it is difficult to provide an integrated assembly whereby the corona tire remains in intimate contact with the remainder of the tertiary winding over the wide range of temperatures encountered in shipping and operation of the transformers. In general, it has been difficult in the prior art device to maintain a continuing compatibility between the impregnating wax and the wax corona tire.

The present invention provides a horizontal output transformer which overcomes the prior art problems while still being non-combustible in the sense that there is insufficient power in the television receiver to ignite the transformer to a point where continuing combustion results.

Accordingly, an object of the invention is to provide an improved horizontal output transformer for a television receiver.

Another object is to provide an improved horizontal output transformer that is non-combustible.

A further object is to provide an improved horizontal output transformer which is easily ventilated to lower operating temperatures and improve reliability.

Yet another object is to provide an improved horizontal output transformer which is more easily fabricated than prior art devices.

These and other objects are achieved in one embodiment of the invention through the use of a non-impregnated layer wound tertiary employing a slow burning polyester film as the insulating material. The primary and ancillary windings are wound directly on a coil form, the primary and ancillary windings then being received by the central opening of the tertiary assembly and attached thereto by a suitable adhesive. A non-combustible naphthalene chloride wax corona tire is then positioned around the tertiary assembly, the naphthalene chloride wax penetrating the interstices between layers of the polyester film insulation to produce an integrated and rugged assembly.

The novel and distinctive features of the invention are set forth in the appended claims. The invention itself together with further objects and advantages thereof may best be understood by reference to the accompanying drawings in which:

FIGURE 1 is a schematic diagram of a representative horizontal output transformer for a television receiver.

FIGURE 2 is a partial exploded perspective view of the horizontal output transformer in accordance with the invention, and

FIGURE 3 is a completely assembled perspective view of the transformer shown in FIGURE 2.

Referring to the representative horizontal output transformer depicted in FIGURE 1, there is shown generally at 1 a winding having first and second end taps 3 and 5 respectively and including an intermediate tap 7. The

3

portion 8 of the winding 1 between the taps 3 and 7 comprises the primary of the transformer while the portion 9 between the taps 5 and 7 comprises the tertiary winding across which the high voltage required for operation of the cathode ray tube is developed. In operation, the tap 7 is connected to the output of the horizontal output stage to couple the desired sweep signal to the primary of the transformer. A high voltage is produced at the high voltage tap 5 and a boost voltage is produced at the tap 3 in conventional fashion. Additional intermediate taps 10 and 11 are provided on the primary of the winding 1, the tap 10 being the conventional yoke tap and thus being connected to the horizontal deflection windings while the tap 11 is the conventional damper tap and accordingly is connected to a suitable damper diode.

In addition to the winding 1, an ancillary winding 13 is provided having end taps 15 and 17. The winding 13 is magnetically coupled to the winding 1 and serves to develop keying pulses across the taps 15 and 17 for the AGC keyer in conventional fashion. In addition to the winding 13 further ancillary windings might be employed. For example, a second ancillary winding might be employed to provide a blanking signal in conventional fashion.

Referring to FIGURE 2 there is shown a horizontal output transformer structure in accordance with the invention, like reference numerals being given to those winding portions identified in FIGURE 1.

The horizontal output transformer of the invention comprises a primary assembly generally shown at 21 and an annular tertiary assembly generally shown at 23. The primary assembly 21 includes a coil form preferably formed from a slow-burning or flame retarding plastic material such as general purpose phenolic. The coil form comprises a generally cylindrical coil supporting portion 25 and an integral generally annular shaped end portion 27 upon which are positioned axially extending terminals 29 in conventional fashion.

The primary portion 8 of the winding 1 shown in FIGURE 1 and the ancillary winding 13 are wound directly on the coil supporting portion 25, the winding as depicted being of the universal type and employing an insulated magnet wire. A length of adhesive coated tape 31 preferably formed from a slow-burning or flame retarding material such as a polyester film having a thermosetting pressure sensitive adhesive deposited thereon, is positioned over the completed primary winding to retain the winding in the desired position.

The tertiary assembly 23 comprises an open ended cylindrical kraft paper coil form 33. The tertiary winding 9 as shown in FIGURE 1 is layer wound about the coil 33, the winding 9 preferably being formed from an insulating magnet wire coated with a solvent activated adhesive material. The winding 9 is layer wound as shown, the number of layers and the number of turns in each layer being determined by the electrical requirements of the transformer.

In accordance with an important feature of the invention, the layers of the winding 9 are insulated one from the other by an interleaved film 35 of a slow-burning polyester material. This material is preferably a polyethylene terephthalate film having a thickness on the order of .002", such as for example the commercially available material Mylar. The slow-burning polyester material 35 plays an important role in rendering the horizontal output transformer of the invention non-combustible. Thus, should a malfunction take place in such a manner that localized heat is generated within the tertiary winding, the film 35 in the heated area will melt prior to burning and has a tendency to thicken upon melting to such an extent that combustion is precluded. Since the slow-burning polyester film is non-hygroscopic the impregnating wax employed in the prior art is obviated and the problems associated with such wax

are eliminated. For example, it is well known that wax has a greater dissipation factor than air and that this factor increases markedly as its temperature approaches the operating levels that these transformers are subjected to, e.g., 80°-125° C. This tends to increase the internally generated heat which, in the extreme, can lead to thermal runaway. By eliminating wax impregnation, thus leaving the turns of the winding immediately surrounded by air, the transformer operates at a lower temperature than heretofore.

As depicted in FIGURE 2, an output terminal 37 is provided, the terminal 37 being attached to the tertiary assembly 23 by a length of adhesive coated tape 39 preferably of the same type employed for the element 31 and the end of the winding 9 being connected to the terminal 37.

It will be seen that since the tertiary assembly 23 eliminates the necessity for wax impregnation by employing a slow-burning polyester film that the tertiary assembly is truly non-combustible in the sense employed throughout this specification.

Referring to FIGURE 3 there is shown the assembled horizontal output transformer in accordance with the invention. As depicted, the central opening in the annular tertiary assembly 23 receives the primary assembly 21, a suitable adhesive being utilized to attach the kraft paper coil form 33 to the tape 31.

In accordance with another important feature of the invention a non-combustible naphthalene chloride wax corona tire 41 is placed around and in intimate contact with the tertiary assembly 23. A conventional high voltage lead 43 is attached to the terminal 37 shown in FIGURE 2. The lead 43 is provided with an end terminal 45 adapted to engage the high voltage cap of a conventional high voltage rectifier tube. A fire retarding air seal material 47 is molded around the terminal 37 as depicted to preclude corona discharge in the vicinity of the terminal. The transformer is completed by attaching the various taps shown in FIGURE 1 to the associated terminal 29 as depicted.

As pointed out above, the horizontal output transformer of the invention is non-combustible as contrasted to the prior art devices due to the use of the slow-burning polyester insulation and the non-combustible naphthalene chloride wax corona tire.

It will be seen that the transformer in accordance with the invention is much easier to fabricate than the prior art device. Thus, the tertiary assembly 23 is easily gang wound utilizing a single wide sheet of polyester film 35, the adhesive coating on the winding 9 being activated by a suitable solvent so that the winding adheres to the polyester film and does not spread apart or "wander" during and after assembly. Even where the surface of the film is too slippery for the winding to adhere, the adherence of adjacent turns to each other is sufficient for this purpose. The various tertiary assemblies can then be separated one from the other by a suitable sawing operation.

The corona tire 41 can be applied to the tertiary assembly 23 either before or after the primary assembly 21 is assembled thereto. If the corona tire is applied prior to assembly, the tertiary assembly 23 is dipped in a hot pool of naphthalene chloride wax. If the corona tire 41 is applied subsequent to assembly, the assembly is supported slightly above the wax pool and parallel thereto so that the tertiary can be rotated through the pool and the corona coating adhered thereto. In either event, it will be appreciated that the corona tire is easily applied to the tertiary assembly 23 since the naphthalene chloride wax quickly freezes to the tertiary assembly 23 and provides a uniform and continuous coating. Further, the naphthalene chloride wax fills the interstices between adjacent layers of the polyethylene terephthalate film and provides an integrated and rugged assembly.

As an alternative to applying the naphthalene chloride wax by a dipping process, it is also possible to use a low

pressure injection molding technique. Such a molding technique has the additional advantage that the air seal material 47 can be eliminated, the naphthalene chloride wax itself being molded to provide the necessary seal.

Thus the horizontal output transformer of the invention provides a non-combustible device which eliminates the necessity for positioning the transformer in a fireproof cage or for over-designing the transformer as was required for the prior art device. Further, due to the non-combustible nature of the transformer of the invention, the transformer is easily mounted in a well ventilated location such as for example directly on a circuit board and accordingly operates at a lower temperature than the equivalent prior art device and thus exhibits a significantly increased reliability. Further, the prior art problems associated with the use of an impregnating wax are completely eliminated and a device is provided which is significantly easier to fabricate.

Although the invention has been described with respect to certain specific embodiments, it will be appreciated that modifications and changes may be made by those skilled in the art without departing from the true spirit and scope of the invention. For example, although a universal wound primary has been shown, it is within the scope of the invention to employ a layer wound primary utilizing a slow-burning polyester film insulation in the same manner as the tertiary winding. Therefore, it is intended by the appended claims to cover all such modifications and changes that fall within the true spirit and scope of the invention.

What we claim and desire to secure by Letters Patent of the United States is:

1. A non-combustible horizontal output transformer for a television receiver comprising:
  - (a) a primary assembly including a coil form having a primary winding positioned thereon,
  - (b) an annular tertiary assembly including an open ended cylindrical coil form having a non-wax-impregnated wire layer wound tertiary winding positioned thereon, adjacent layers of said tertiary wind-

ing being separated by a layer of non-hygrosco insulating material formed from a slow-burning polyester film,

(c) said tertiary assembly being positioned in coax and surrounding relationship to said primary winding and being affixed thereto, and

(d) a naphthalene chloride wax corona tire overlain on said tertiary assembly in intimate contact therewith

2. The horizontal output transformer defined in claim 10 wherein said insulating material is a polyethylene terephthalate film.

3. The horizontal output transformer defined in claim 15 wherein said naphthalene chloride wax corona tire extend into the interstices between adjacent layers of said poly ester film.

4. The horizontal output transformer defined in claim 20 wherein said layer wound tertiary winding is wound from an insulated magnet wire having an adhesive coating positioned thereon.

5. The horizontal output transformer defined in claim 25 4 wherein said adhesive coating comprises a solvent activated adhesive.
